[57] CLAIM

The ornamental design for a cosmetic container, substantially as shown and described.

DESCRIPTION

FIG. 1 is a perspective view of a cosmetic container showing my new design;

FIG. 2 is an enlarged top plan view of the cosmetic container shown in FIG. 1;

FIG. 3 is an enlarged elevational view of the cosmetic container shown in FIG. 1 from a front side;

FIG. 4 is an enlarged elevational view of the cosmetic container shown in FIG. 1 from the side opposite that of FIG. 3; and

FIG. 5 is an enlarged bottom view of the cosmetic container shown in FIG. 1.
